UNITED STATES PATENT OFFICE.

LAWRENCE E. BAER, OF ATTLEBORO, MASSACHUSETTS, ASSIGNOR TO BAER & WILDE COMPANY, OF ATTLEBORO, MASSACHUSETTS.

BUCKLE.

Application filed September 26, 1921. Serial No. 503,125.

To all whom it may concern:

Be it known that I, LAWRENCE E. BAER, a citizen of the United States, residing at Attleboro, in the county of Bristol and State 5 of Massachusetts, have invented new and useful Improvements in Buckles, of which the following is a specification.

This invention relates to certain new and useful improvements in buckles, and relates 10 more especially to a buckle which is formed for enabling the belt ends to be connected and disconnected while maintaining a fixed relation to the belt, or in other words without disturbing the predetermined diameter 15 of the belt.

The primary object of the present invention is to provide improved means for enabling the belt ends to be easily and quickly connected and disconnected.

20 A further object of the invention is to provide means for connecting the two parts of the buckle, which means are formed integral with each of the buckle parts.

The invention further aims to provide 25 means which are of simple and economical character and which are devoid of all moving parts.

Further and other objects will be later set forth and manifested in the course of the 30 following description.

In the drawings:

Figure 1, is a rear side elevation;

Figure 2, is a section on line 2—2 of Figure 1;

35 Figure 3, is a section on line 3—3 of Figure 1; and

Figure 4, is a view similar to Figure 1 of a modified form of the invention.

In proceeding in accordance with the present invention, the buckle is composed of a front member 1 of approximately hollow formation having its side edges 2 rolled over to hold the flanges 3 of a back plate 4 against the rear face of the body of the member 1 as shown in Figure 3 of the drawings. The back plate 4 has approximately T-shaped heads 5 struck out therefrom, the heads 5 forming male members which are receivable in corresponding openings 6 formed in the 45 plate 7 that constitutes the rear member of the buckle, the latter having a bail 8 to which one end of the belt is permanently secured. The opposite end of the belt is passed through the hollow front member 1 between 50 the back plate 4 and the body of the front

member and is adjustably clamped against the rear of the body of the front member by a clamping screw or device 9. It will be understood that after the belt has been adjusted as to its diameter the screw 9 is operated to clamp the belt end extending within member 1 firmly to the latter, and this adjustment is maintained definitely throughout as long a period as desired. It will now be seen that the belt may be applied and removed without disturbing the diameter thereof by merely relatively sliding the front and back members 1 and 7 so as to cause the heads 5 to enter the enlarged parts of the slots or openings 6, following which the 70 heads 5 are disengaged from the plate 7 by merely laterally moving the parts 1 and 7 away from each other, or spreading same. In the preferred form of the invention there are two fastenings employed, located on the 75 respective opposite sides of the clamping device 9, while in Figure 4 of the drawings but one fastening is employed.

From the foregoing it will be seen that the fastenings for connecting the members 1 and 7 are devoid of all moving parts and are moreover integral with each of the respective members, and since the outward pressure of the body of the wearer on the belt acts to cause the plate 7 to move in a direction in which the narrow ends of the openings 6 abut the stems or shanks of the heads 5, accidental disengagement of the parts is virtually assured against. The opening 10 in the plate 7 is merely formed for the purpose of accommodating the handle of the clamping device 9 so that the plate 7 can be removed and applied accordingly.

Having thus described my invention, what I claim as new and desire to secure by Letters Patent is:—

1. In a belt buckle, a hollow front member formed to receive one end of the belt therein and having a back plate formed with a spaced pair of T-shaped heads struck out 100 therefrom, means between said heads to fixedly secure said end of the belt to the front member, and a back member including a plate having means to fixedly secure the opposite ends of the belt thereto and having a 105 pair of T-shaped slots to receive said heads so as to connect the members upon movement of the same to bring the shanks of the head into the narrowed parts of the slots.

2. In a belt buckle, a front member formed 110

hollow to receive one end of the belt therein, means to secure the belt to said member, upper and lower outwardly projecting parts on the back of the front member, a back member engageable with the back of the front member and having means to secure the opposite end of the belt thereto, one of the belt end securing means being adjustable, and a head and socket connection between the back of the front member and the back member to connect and disconnect the members by a relative lateral and sliding movement between the two, the back member having its side portions engaged with the said outwardly projecting parts on the back of the front member to assist in holding the back member in position.

3. In a belt buckle, a hollow front member formed to receive one end of the belt therein and having a back plate formed with a spaced pair of T-shaped heads integral therewith, means between said heads to fixedly secure said end of the belt to the front member, and a back member including a plate engaged with the rear face of the back plate of the front member and having means

to fixedly secure the opposite ends of the belt thereto and having a pair of T-shaped slots to receive said heads so as to connect the members upon movement of the same to bring the shanks of the head into the narrowed parts of the slots.

4. In a belt buckle, a front member formed hollow to receive one end of the belt therein, means to secure the belt in said member, a back member engageable with the back of the front member and having means to secure the opposite end of the belt thereto, one of the belt end securing means being adjustable, and a head and socket connection between the back of the front member and the back member to connect and disconnect the members by a relative lateral and sliding movement between the two.

In testimony whereof I have signed my name to this specification in the presence of two subscribing witnesses.
